FLOOR DRIER OR THE LIKE

Frank C. Houser, Granada Hills, Calif., assignor to Nobles Engineering and Manufacturing Company, St.
Paul, Minn., a corporation of Minnesota

Application December 23, 1957, Serial No. 48,999

Term of patent 14 years

(Cl. D9—2)

Figure 4 is a fragmentary rear elevational view of the dryer with the upper portion of the tank and handle omitted for convenience of illustration only.

I claim:

The ornamental design for a floor drier or the like, substantially as shown.
